UNITED STATES PATENT OFFICE.

WALTER E. PIPER, OF SUDBURY, MASSACHUSETTS.

OVERSHOE PATTERN.

Application filed October 27, 1926. Serial No. 144,416.

My present invention is a novel and improved pattern for use in the manufacture of overshoes, and more particularly in the type of overshoes utilizing automatic closures or slide fasteners of the metallic type.

In my prior Patent 1,598,878, issued September 7, 1926, I have illustrated one form of pattern utilizable in overshoes of this type, more particularly the type of overshoes described and claimed in my co-pending application Serial No. 94,295, filed March 12, 1926.

An important feature of my present invention is that by utilizing the novel pattern illustrated herein, the entire upper shoe structure may be accurately cut, fitted and made, having the metallic fasteners and closure at the side, and substantially along the line of least distortion imparted to the shoe during walking. I also so form my present pattern so that a gusset, to be applied to the front top portion of the overshoe with the cuff attached thereto, may be cut from said pattern. This simplifies the manufacture of this overshoe by reducing the number of parts to be cut, as well as the number of parts to the pattern. The provision of the gusset in the front upper part of the overshoe also provides sufficient "give" or elasticity, to take care of the varying distortions imparted to the shoe during walking. Preferably the gusset is cut from the same material as the rest of the overshoe upper, so that, when applied to the overshoe, there is apparently no variation in the symmetry or appearance of the overshoe materials. I believe that my present pattern is novel, and I have therefore claimed the same herein broadly.

Referring to the drawings, illustrating a preferred embodiment of my invention,

Fig. 1 illustrates the pattern from which the quarter and upper section is cut;

Figs. 2 and 3 illustrate, on a reduced scale, the outer pocket or fan and fan lining patterns;

Fig. 4 illustrates the pattern from which the inside lining is cut;

Fig. 5 illustrates the gusset and cuff pattern;

Fig. 6 illustrates the cuff lining pattern; and

Fig. 7 illustrates the fastener stay pattern.

As shown in the drawings, my novel pattern comprises the component parts 1, 2, 3, 4, 5, 6, and 7. 1 is the pattern from which

the quarter and upper section, complete in a single piece, except for the gusset, is cut. In the pattern 1, is a slot 8 representing, in the cutout, quarter, the cut or slot for insertion and securing of the gusset 5. In order to afford a neat and attractive appearance in the completed overshoe, I provide a thread line 9, here illustrated as extending from the bottom of the slot 8 across the surface of the pattern directly to the toe thereof. When positioning the pattern on the material to be cut, this thread line will be placed according to the thread or "grain" of the cloth, or along the warp thereof, so that in the finished overshoe the cloth or upper material will not present a distorted appearance, but will have the distinct line of the fabric running from a line drawn from the bottom of the slot 8 to the toe, in a symmetrical sweeping line therefrom. This is an important feature, and one that I believe is new in my present invention.

2 designates the pattern from which the "fan" or pocket, which automatically adjusts itself to the size of the leg of the wearer, is cut, and 3 is the pattern from which the inside layer or lining of the "fan" 2 is cut. It will be noted that the pattern 3 is larger than the pattern 2, being wider to provide overlapping edges for cementing. The pattern 3 is also provided with flaps 10, extending below the bottom of the pattern 2, for cementing or securing to the adjacent portions of the completed overshoe. This fan or pocket is constructed inside the overshoe, and on the same side as the automatic metallic closure, viz, on the "inside" of the shoe.

The pattern 4 is adapted to be utilized in cutting out the inside lining of the overshoe, the one pattern sufficing for the lining for both sides of the overshoe. The pattern 4 is provided with a slit or slot 11, which slot is intended to be utilized in one side of the lining only, viz, that side which is interrupted by the metallic fastener.

The one combination pattern 5 provides for the cutting out of the gore or gusset and fastener cuff, and has a line 12 indicating the line of fold of the cuff.

The pattern 6 is adapted to provide for the cutting out of the inside layer of the cuff, preferably of the same material, and has a line of fold 13, as well as notches 14, if desired, to designate the line of fold in the cutout cuff lining, for securing to the

outer cuff and also a flap 15 for securing to the lining of the overshoe. A notch 16 is formed in the pattern 5, the edges 17 and 18 representing the edges of the cutout gusset 5 which are cemented or otherwise secured under the edges of the slot 8 in the quarter 1.

From the pattern 7 is cut the fastener stay which is secured to the lining and has a slot 19 adapted to aline with the slot 11 in the lining 4, and with the opening or slot 20 in the quarter 1, and to the sides of which slot 19 are secured the interlocking sides of the automatic metallic closure or fastener. The fastener stay 7 will, of course, follow 15 the same inclination or angle indicated for the slot 11 in the lining 4.

The edges 21 and 22 of the cutout quarter 1 will meet in a straight line at the back of the shoe, so that the line of contact of 20 these edges of the upper or quarter will be in the most out of the way place, and not apparent to observation, except from the rear of the shoe.

With the metallic fasteners secured to the 25 opposite edges of the closure corresponding to the slots 11, 19 and 20, and substantially along a slightly diagonal line from a position preferably over the arch of the foot up to a point directly midway of the forward 30 and rearward portions of the top of the overshoe, I secure the advantages of having the entire metallic fastener and interlocking parts when closed in practically a non-movable or non-distorting line, during the necessary flexing of the overshoe while the wearer 35 is walking. Furthermore, by the use of my novel combination gusset and cuff I secure a better, easier, and smoother fitting over the instep, due to the elasticity imparted by the 40 gusset. Thus, by the use of my novel pattern I am enabled to produce an improved overshoe with lasting qualities, and yet embodying the advantages of a neat front portion and a metallic fastening. I believe that 45 my novel pattern utilized in the construction of such an advantageous and improved overshoe, is novel, and the same is therefore claimed broadly herein.

My invention is further described and defined in the form of claims as follows:

1. A pattern for use in the manufacture of overshoes provided with metallic slide fasteners, consisting of component parts comprising respectively a quarter, fan sides, 55 lining, combined gusset and cuff, cuff lining,

and fastener stay, said quarter being provided with a thread line to indicate the position of the thread of the upper fabric in the completed overshoe, said quarter having a slot to indicate the position of the combined gusset and cuff, said lining having a slot alined with a slot in said quarter to indicate the position of the fastener on the side of the overshoe.

2. A pattern for use in the manufacture 65 of overshoes provided with metallic slide fasteners, consisting of component parts comprising respectively a quarter, fan sides, lining, combined gusset and cuff, cuff lining, and fastener stay, said quarter being provided with a thread line to indicate the position of the thread of the upper fabric in the completed overshoe, said quarter having a slot to indicate the position of the combined 70 gusset and cuff, said lining having a slot alined with a slot in said quarter to indicate the position of the fastener on the side of the overshoe, and said fastener having a slot alined with the slot in the lining, said three 75 slots adapted to be in a predetermined alinement on the inner side of the overshoe.

3. A pattern for use in the manufacture of overshoes provided with metallic slide fasteners, consisting of component parts comprising respectively a quarter, fan sides, 80 lining, combined gusset and cuff, cuff lining and fastener stay, said combined gusset and cuff being provided with a line to indicate the line of fold of the cuff and with a notch to indicate the extent of the material of the 85 gusset which is to be secured to the side of the gusset slot in the quarter, and said cuff lining being provided with notches and a line extending between said notches to indicate the line of fold of the cuff lining, said 90 quarter being provided with a thread line to indicate the position of the thread of the upper fabric in the completed overshoe, said quarter having one slot to indicate the position of the combined gusset and cuff, said 95 lining having a slot alined with another slot in said quarter to indicate the position of the fastener on the side of the overshoe, and said fastener stay having a slot alined with the slot in the lining said three slots adapted 100 to be in a predetermined alinement on the inner side of the overshoe.

In testimony whereof, I have signed my name to this specification.

WALTER E. PIPER.
